UNITED STATES PATENT OFFICE.

SYLVANUS SAWYER, OF FITCHBURG, MASSACHUSETTS.

MACHINE FOR SPLITTING RATANS INTO STRIPS.

Specification of Letters Patent No. 12,141, dated January 2, 1855.

To all whom it may concern:

Be it known that I, SYLVANUS SAWYER, of Fitchburg, in the county of Worcester and State of Massachusetts, have invented a new and useful Machine for Splitting Ratan into Strips or Parts and Reducing or Finishing the Same; and I do hereby declare that the same is fully described and represented in the following specification and the accompanying drawings, letters, figures, and references thereof.

Of the said drawings, Figure 1, denotes a top view of my said machine; Fig. 2, is a side elevation of it; Fig. 3, is a vertical, central, and longitudinal section of it; Fig. 4, is a rear end view of it; Fig. 5, is a horizontal section exhibiting the gearing applied to the shafts of the feeding rollers; Fig. 6, is a vertical section of the guide stock such section being taken transversely of the machine and so as to exhibit the movable dies of said stock; Fig. 7, is a front end elevation of the radial wing cutter (and its stock) by which the ratan is reduced to strips of sectoral section; Fig. 8, is a rear end elevation of the said radial wing cutter and its stock; Fig. 9, is a horizontal section of it taken so as to exhibit two opposite springs thereof; Fig. 10, is a front, and Fig. 11, is a rear end view of the cutter and stock for removing the annular strands and rounding or dressing the triangular strips or pith sections of the ratan after the outer parts or strands have been removed; Fig. 12, exhibits a transverse section of a stick of ratan and the manner in which it is first reduced to sectoral strips *a, a, a*; Fig. 13, denotes a transverse section of such ratan and represents the manner in which each of the sections, *a*, of it is divided into two parts by the annular cutter; Fig. 14, exhibits another transverse section of a piece of ratan and the manner in which each of the strips *c, c*, is reduced by its rounding or finishing cutter.

By means of my machine a stick of ratan is not only split into sectoral parts or strips, but each of these strips is subsequently reduced to a strand (for the manufacture of chair seats) and a triangular or sectoral strip which by the machine is rounded so as to be of use in the manufacture of bonnets or for many other useful purposes in the arts.

Having thus premised, I will now proceed

to describe the construction and elementary parts of my invention.

In the drawings, A, represents the framework by which the operative parts of the machine are supported, such framework being of any proper form or material. At what I term the front end of the machine there is placed an introductory guide, B, which consists of a frustoconical tube or mouth piece for the correct introduction of a stick of ratan into the bite of the first pair of feed rollers, C, C; there being of such pairs of feed rollers such a number as occasion may require. These sets of feed rollers are arranged horizontally above the top plate of the frame each roller being sustained upon the upper end of a vertical shaft, D. Each pair of feed rollers like those used in various well known machines for splitting ratan is sustained by such contrivances or mechanism as will admit of its two rollers being pressed toward one another by means of a spring, such spring being shown at E. The shafts of said rollers are sustained, at their upper ends, in movable boxes F, F, that are connected to an upright rod, G, by toggles or links, H, H. The spring, E, envelops said rod and forces it downward and thus causes the rollers to be pressed toward one another. A vertical section of a pair of feed rollers and the mechanism above mentioned for forcing them together is exhibited in Fig. 15.

The lower end of each feed roller shaft is provided with a rocker box or slip I, such rocker box being simply sustained by journals such as will admit of the necessary lateral movement of the shaft supported by it. Above their rocker boxes, each pair of shafts is fitted with gears of equal dimensions as seen at K, K; those of each pair of shafts being made to engage with one another.

A driving gear and the connecting gears N, O, are used in connection with the gears, K, K, of the shafts D, D, on one side of the machine as seen in the drawings, and particularly in Fig. 5, thereof; the said driving gear being mounted upon a driving shaft P. After passing through the feed rollers by which it is forced onward, the ratan is introduced into the guide stock, Q, and by it is guided to the radial wing cutter, R. This guide stock consists simply of a circular box, d, and four movable dies or guides e, e, e, e arranged as seen, in Fig. 6; the said

dies being provided with springs, *f*, *f*, by which they are forced inward toward one another. Such springs are arranged within the box as represented in Fig. 6. These dies 5 are caused to operate in pairs so that those on the opposite side of the stick of ratan may respectively have the same amount of movement either toward or away from it; and for this purpose one of each pair is 10 made with an arm, *g*, which extends toward the opposite side of the box or stock as shown in Fig. 6, and is jointed to or made to engage with one end of a balance lever whose other end is similarly jointed to or 15 made to engage with the opposite or fellow die. After passing through the guide stock, *Q*, or between its dies, the ratan is directed by them and is forced against a radial wing cutter, *R*, such cutter being constructed of 20 a series of chisels *k*, *k*, *k*, disposed with their cutting edges in radial directions and further arranged as seen in Figs. 7, 8, and 9.

Between each adjacent two of the cutters there is a spring, *l*, which is affixed to the 25 cylindrical, tubular box, *m*, by which the radial wing cutter is sustained. The said spring, *l*, serves to force a sectoral strip of cane close down into the angle of the cutters between which said strip is placed, and 30 thereby insure the proper direction of the strip to the annular cutter, *S*.

The radial wing cutter separates the ratan into sectoral strips or parts as seen at 35 *a*, *a*, *a* in Fig. 12. In rear of the said radial wing cutter is arranged the said annular or tubular cutter, *S*, which is supported by and in a tubular stock, *T*, and with its axis in line of that of the radial wing cutter. The front end of this annular cutter or that next to 40 the wing cutter should be ground sharp, and it may be either circular, triangular, or polygonal in shape as occasion may require, the object of such annular cutter being to separate from each of the several sections 45 *a*, *a*, *a*, of ratan what is usually termed the strand, *b*, see Fig. 13. Such strand having on its outer surface the enamel or silicious covering of the ratan. Within the annular ring cutter there is arranged a series of tubular cutters, *n*, *n*, *n*, as seen in Figs. 10 and 50 11, and also in Fig. 3. The object of these

tubular cutters is to round off the angles of the parts or triangular portions, *c*, *c* (Fig. 13) of the pith or middle part of the ratan, and to finish such parts, (*c*, *c*), so as to render them available as hereinbefore mentioned. Heretofore it has been customary either to use the pith of the ratan in a solid or cylindrical shape, or to separate the whole ratan into sectoral strips and subsequently 60 waste the pith part of each sector by reducing it down so as to leave the segmental strip or strand.

By my machine the pith is saved and separated into strips, and each strip finished 65 or dressed so as to render it an article of use as hereinbefore stated.

Having thus described my machine, I would remark that I do not confine my invention to the precise form or construction 70 of any one or more of its parts so long as I do not substantially change the character or principle of my invention.

What therefore I claim in the same is—

1. A combination of mechanism for splitting the ratan into sectoral strips and a mechanism for removing annular or segmental strands therefrom substantially as above specified. 75

2. I also claim a combination of mechanism for splitting a stick of ratan into sectoral, or triangular parts or strips, and a mechanism for rounding and dressing or finishing either one or more such strips substantially as specified. 80

3. I also claim a combination of mechanism for splitting a ratan into sectoral parts or strips, a mechanism for removing or separating from such parts annular or segmental strands as specified, and mechanism for rounding, reducing or finishing either one or more or all of the triangular strips or parts of the pith or inside portions 85 of the ratan as specified.

In testimony whereof I have hereunto set 90 my signature this eleventh day of October A. D. 1854.

SYLVANUS SAWYER.
